UNITED STATES PATENT OFFICE

155,326

DESIGN FOR AN EARRING OR SIMILAR ARTICLE

William Wienner, New York, N. Y., assignor to Reinad Novelty Co., New York, N. Y.

Application April 12, 1949, Serial No. 1,918

Term of patent 3½ years

(Cl. D45—9)

To all whom it may concern:

Be it known that I, William Wienner, a citizen of the United States of America, residing in New York city, county of Kings, and State of New York, have invented a new, original, and ornamental Design for an Earring or Similar Article, of which the following is a specification, reference being had to the accompanying drawing, forming part thereof, wherein,

I claim:

The ornamental design for an earring or similar article, substantially as shown.

WILLIAM WIENNER.
